UNITED STATES PATENT OFFICE.

GRANT B. SHIPLEY, OF PITTSBURGH, PENNSYLVANIA.

WOOD-TREATING PLANT.

Application filed May 10, 1922. Serial No. 559,807.

To all whom it may concern:

Be it known that I, GRANT B. SHIPLEY, a citizen of the United States, and a resident of Pittsburgh, in the county of Allegheny and State of Pennsylvania, have invented a new and useful Improvement in Wood-Treating Plants, of which the following is a specification.

This invention relates to an apparatus for treating wood or timber and particularly to an apparatus for treating ties or other similar articles with an antiseptic solution, such as creosote, zinc-chloride, or sodium fluoride.

The principal objects of the invention are to provide a treating plant of the character referred to which will be economical to install, which will require the minimum power to operate, which will reduce the time ordinarily required for treating the timber thus resulting in an increased output, which will be self contained, which will be efficient in operation, and which will be adapted for carrying out either of the so-called "full-cell" or "empty-cell" processes.

It is a special object of the invention to provide a treating plant in which peak loads upon the several units employed will be obviated, the necessary power for operating the several units being stored gradually over a considerable period of time under efficient operating conditions, instead of overtaxing the said units during the comparatively short intervals of time while actually needed and then allowing the same to remain idle over an extended period.

Heretofore, in treating plants of this character, it has been the practice to produce the necessary pressure required in the several tanks containing the preservative fluid as well as in the treating cylinder itself, by means of direct-connected pumps of large capacity requiring a great amount of power to operate, thus rendering the operation of the same un-economical, or by creating the necessary pressures by similar pumps which must necessarily be operated over an extended period of time, thereby reducing the output of the plant. In plants employing processes involving the employment of a vacuum or reduced pressure, it has also been the practice to create this vacuum or low pressure by means of large and expensive direct-connected pumping devices, or by those of less capacity which are required to be operated for longer periods.

These vacuum creating devices are, therefore, also objectionable and give rise to similar disadvantages to those incident to the means for creating high pressures, above noted. The use of large capacity direct-connected pumping devices in these plants has proved very expensive and uneconomical in operation, necessitating operation under peak loads, and the use of the smaller capacity pumping devices have not only reduced the output of the plant, but also have been found objectionable for the reason that the preservative could not be introduced into the treating compartments at such a rate as to assure all portions of the material being subjected to uniform treatment, hence resulting in an objectionable product because of its non-uniformity.

It is still a further object of the invention to obviate the necessity of pumping devices of extremely large capacity, and to enable economical pumping devices of smaller capacity to be employed in combination with pressure and vacuum storage tanks, in such manner that the time of treatment of a charge may be reduced to the minimum and in which the character of the treated product will be substantially uniform.

It is still a further object to provide a wood treating plant utilizing pressure and vacuum tanks in combination with measuring and treating cylinders so proportioned as to size that the desired pressures may be directly and quickly obtained in the measuring and treating compartments by merely establishing communication between them and the storage receptacles.

Other objects of the invention are to provide a treating plant which will be self-contained and one in which the vapors passing from the several compartments will be condensed and treated in such a way that the same may be returned either directly to the treating cylinder or to suitable storage tanks provided for such purpose.

Still other objects of the invention will readily appear from the following descriptions when taken in connection with the appended claims.

In the accompanying drawings, Fig. 1 is a diagrammatic plan view of the preferred embodiment of the invention; Fig. 2, a diagrammatic side elevation of the form shown in Fig. 1; and Fig. 3, a diagrammatic end elevation of the same.

- 2
- In the drawings, 1 designates the usual treating cylinder provided with the hinged door 2, the open position of which is indicated by the dotted lines in Fig. 1. Superposed above the treating cylinder 1, is an oil-working tank 3 in one end of which is located the pressure measuring tank 4, extending from the bottom of which is a conduit 5 leading to the top of the treating cylinder, this conduit being provided with the controlling valve 6. The bottoms of the oil-working tank and the treating cylinder are connected by the conduit 7 having the interposed valves 8 and 9.
- 10 In order to furnish a supply of air under pressure, the air-storage tanks 10 and 11, supplied by the air compressors 12 and 13 through pipes 14 and 15, are provided. Suitable cut-off valves 16 and 17 are interposed in the pipe lines 14 and 15 so as to enable the pumps to be discontinued from the system should it become necessary, the said pipes discharging into the air storage tanks through the branches 18 and 19 of a pipe connecting the two storage tanks and provided with the valves 20, 21 and 22, so that by proper manipulation of the several valves either or both of the air storage tanks may be used, as desired.
- 15 A branch pipe 23 provided with the valve 24 leads from the discharge pipe 14 into a manifold 25, and a similar branch pipe 26 provided with the control valve 27 leads from the discharge pipe 15 into the same manifold. Suitable cut-off valves, 28, 29 and 30 are located in the manifold 25, and interposed between the branch pipe 26 and valve 30 is a suitable pressure reducing valve 31, a similar reducing valve 32 being disposed between the branch pipe 23 and valve 29. Extending from one end of the manifold 25 is a pipe 33 leading to the top of the pressure measuring tank 4, a control valve 34 being interposed therein. Extending 20 from the opposite end of the manifold is a pipe 35, having a control valve 36, which leads to the top of the oil-working tank, and also extending from the same end of the manifold is a pipe 37 having the interposed valves 38 and 39 which leads to the top of the treating cylinder, the pressure supply pipe 40 being connected to the pipe 37 between the valves 38 and 39.
- 25 A second manifold 41 is provided from which the pipes 42, 43 and 44 lead to the pressure measuring tank, treating cylinder, and oil-working tank, respectively, the manifold being equipped with the valves 45 and 46 and the pipe 43 with the valve 47. The manifold 41 is also provided with a branch conduit 48, controlled by the valve 49, leading to the atmosphere.
- 30 Extending from manifold 41 at a point intermediate the pipes 43 and 48 is a conduit 50 provided with the valve 51 which

leads to a barometric condenser 52, the hot well of which is indicated at 53, the condenser being equipped with the usual overflow and drain pipes shown at 54 and 55, respectively. The cooling water for the condenser is supplied through the pumps 55^a having the usual suction conduit 55^b and discharge line 55^c.

35 Located at one side of the condenser 52 is a vacuum tank 56, the tops of the condenser and vacuum tank being connected by the pipes 57 and 58, the latter of which is provided with the valve 59, and extending from the juncture of pipes 57 and 58 is a conduit 60 which connects with the branch conduits 61 and 62 leading to the vacuum pumps 63 and 64, respectively, control valves 65 and 66 being interposed in the branch conduits.

40 The hot well 53 is provided with an overflow pipe 67 which is tapped into a drain pipe 68 provided with the valve 69 leading from the bottom of the vacuum tank to a settling pond or sump 70, the sump being merely an open receptacle for receiving the liquid collecting in the hot well and the condensate collecting in the vacuum tank after continued use. The centrifugal pump 71 has its inlet pipe leading from the opposite end of the settling pond or sump and is adapted to discharge the contents thereof through discharge pipe 72 into the dewatering tank 73.

45 Leading from the lower end of the dewatering tank is the suction conduit 74 of a centrifugal pump 75, the discharge line 76 of which is branched, the branch 77 leading to the conduit 7 connecting the bottoms of the treating cylinder and oil-working tank, while the branch 78 discharges into an oil storage tank 79. The suction conduit 74 is provided with the cut-off valves 80 and 81 between which a pipe 82 having cut-off valves 83 and 84 extends, being connected to the branch 78 as at 85. Suitable cut-off valves 86, 87 and 88 are interposed in the branch conduits 77 and 78, and a branch pipe 89 having the cut-off valve 90 extends from the pipe 77 to the branch 78 between the valve 87 and the oil storage tank. In order to discharge the preservative directly from the pump 75 into the pressure measuring tank, a branch pipe 91 having a valve 92 is provided.

50 In order to control the valve 59 from a point adjacent the pumps and treating cylinder, the same is connected to a pressure actuated motor 96 to which pressure fluid from the pipe 40 is supplied and exhausted through the conduits 97 and 98, the flow of the pressure fluid being controlled by a four-way cock indicated at 99, the pressure motor 96 being merely a pressure cylinder with the usual piston and functions in the well known way.

Pressure fluid is supplied by the pumps 12 and 13 to the air storage tanks 10 and 11, the normal pressure of the fluid in the tanks being maintained at about 350 pounds 5 pressure per square inch, and the pumps 63 and 64 normally maintained a vacuum in the tank 56 amounting to about 24 or 26 inches of mercury. The pressure of the air from the storage tanks in passing the 10 reducing valve 31 is lowered to about 200 pounds pressure per square inch which is that ordinarily employed in the pressure measuring tank for forcing the preservative into the wood, while the pressure reducing 15 valve 32 is adjusted to reduce the air pressure to about 60 to 100 pounds pressure per square inch depending upon the character of the wood or timber being treated.

The relative sizes of the air storage tanks 20 10 and 11 and that of the pressure measuring tank 4 are so proportioned that when either of the air storage tanks is put into communication with the measuring tank, due to the equalization of the pressures therein, a resulting 25 pressure will be obtained which will correspond to that required in the measuring tank to force the maximum quantity of preservative into the charge of timber within the treating cylinder. The size of 30 the vacuum tank 52 is likewise so proportioned, that the equalization of pressures within the said tank and treating cylinder will produce a resulting minimum low pressure desired during the drying of the treated 35 timber.

The apparatus and plant described is adapted for carrying out the treatment of materials either by the so-called "full-cell" process or the "empty-cell" process.

In use, the pressure measuring tank 4 and oil-working tank 3 are first filled with the preservative with which the charge of timber is to be impregnated, the air storage tanks filled with compressed air to substantially 45 350 pounds pressure, and a vacuum of about 24 to 26 inches established in the vacuum tank 56. The charge of timber to be treated is then placed within the treating cylinder and the door 2 closed and sealed 50 in the usual manner.

The method of carrying out the "full-cell" process is as follows:

In order to introduce the preservative into the treating cylinder, the top of the treating cylinder is vented to the atmosphere by opening valves 47 and 49, and the valves 8 and 9 are opened to permit the preservative to flow by gravity from the oil-working tank through the conduit 7 into the treating cylinder, the conduit 7 being of sufficient size to permit the treating cylinder to be filled quickly. After the treating cylinder has been completely filled with the preservative the valves 47, 49 and 8 are closed. The valve 65 6 is then opened establishing communica-

tion between the pressure measuring tank and the treating cylinder, and high pressure fluid from either tank 10 or tank 11 is admitted above the preservative in the measuring tank by opening valve 34 and either 70 valve 27 or valve 24. The air from the storage tank is reduced in pressure in passing through reducing valve 31 to about 200 pounds per square inch, forcing the preservative from the pressure measuring tank 75 into the treating cylinder under that pressure. As above pointed out the relative proportions of the air pressure tank and the measuring tank are such that upon equalization of the pressures within the said tanks, 80 which equalization takes place almost immediately upon opening the valve 34, the maximum quantity of preservative desired will be forced into the charge of timber within the treating cylinder. After the pressure in the said tanks has become equalized, and the preservative forced from the measuring tank to the treating cylinder, valves 34 and 6 are then closed.

After the charge of timber has been thus treated by forcing additional preservative into the treating cylinder under pressure, the valve 46 on the atmospheric line 44 of the oil-working tank and the valve 8 in conduit 7 are again opened in order to permit the 90 "kick-back" of the compressed air within the timber to cause a back flow of the preservative from the treating cylinder through conduit 7 to the oil-working tank. Before this back flow has been completed by the 100 "kick-back" action, the top of the treating cylinder is put under air pressure from the air storage tank by opening the valve 39 to permit the air to pass through pipe 37 to force all of the preservative from the treating cylinder to the oil-working tank, during such operation the oil-working tank being continually vented to the atmosphere through the pipe 44 and valves 46 and 49, as 110 above noted.

After all of the preservative has been discharged from the treating cylinder in this manner all the valves previously opened are closed, and the treating cylinder put into communication with the vacuum tank 56 115 through the pipe 43, valve 47, manifold 41, valve 51, pipe 50, the condenser 52 and pipes 57 and 58, the valve 59 being open. The relative proportions of the vacuum tank and the treating cylinder are such that as soon as communication is established, the pressure within the treating cylinder is quickly reduced to the desired minimum pressure within the treating cylinder. The reduction in pressure within the treating cylinder creates a violent boiling of the preservative with which the charge of timber has been impregnated, resulting in a quick drying thereof. Instead of reducing the pressure within the 120 treating cylinder to the extreme minimum 125 130

pressure desired by equalizing the pressures within the vacuum tank and cylinder directly, the pressure within the treating cylinder may be quickly reduced to about 15 inches of mercury by such equalization. Valve 59 is then closed and the pressure subsequently reduced from this point to the desired minimum of about 24 to 26 inches by the pumps 63 and 64 which are connected to 10 the treating cylinder by opening valves 65 and 66, the arrangement of valves being such as to permit the use of one or both pumps as desired. After the pressure has been reduced to the desired minimum within the 15 treating cylinder, the pumps are operated until the charge of timber has been sufficiently dried to be removed therefrom.

Due to the fact that high pressure fluid is always available in the tanks 10 and 11, and 20 low vacuum available in the vacuum tank, the entire treatment of the charge may be performed within a very short period of time, the time required for impregnating the charge and for creating the vacuum within 25 the treating cylinder ranging from 15 to 30 minutes, whereas in the usual practice in which the preservative is pumped from the measuring tank to the treating cylinder and the pressure within the treating cylinder reduced by pumping devices, the total time consumed in the two operations being usually not less than 2 to 3 hours.

After the charge of timber has been treated in the above manner, the same is discharged from the treating cylinder through 35 door 2, and a new charge placed therein in the usual well known manner.

In carrying out the so-called "empty-cell" process, after the charge of timber has 40 been placed within the treating cylinder and the same sealed, compressed air is introduced from the air storage tanks in both the treating cylinder and the oil-working tank by opening the valves 39 and 36, thus 45 permitting the air at the pressure for which reducing valve 32 is adjusted to pass there-to. The setting of valve 32 depends upon the character of the wood being treated and usually varies from about 60 to 100 pounds 50 per square inch. After the treating cylinder and working tank are filled with air, the valves 36 and 39 are closed. Communication is then established between the tops of the oil-working tank and treating cylinder through 55 pipes 43 and 44 and valves 46 and 47, and the preservative permitted to flow by gravity from the oil-working tank through the conduit 7 by opening valve 8. After the treating cylinder has been completely filled with 60 preservative in this manner the several valves are closed, and the measuring tank put into communication with the treating cylinder by opening valve 6. Compressed air at 200 pounds pressure per square inch 65 is then admitted above the preservative in

the measuring tank by opening valve 34. The preservative is thus forced under pressure into the treating cylinder in the same manner as in the previously described "full-cell" process, and the remaining series of 70 operations are identical to those previously set forth in connection therewith.

During the time the treating cylinder is placed under vacuum, any vapors of the preservative passing therefrom are condensed in the barometric condenser 52, the condensate collecting in the hot well 53. This condensate flows to the settling pond or sump 70 from which it is withdrawn by the pump 71 and forced into the dewatering 75 tank 73. The recovered preservative is withdrawn from the dewatering tank by means of the pump 75 and forced either directly into the oil-storage tank 79 through pipes 76 and 78 for future use, or pumped 80 back into the measuring tank and oil-working tank through pipe 77 and the branches leading therefrom to the said tanks.

The pump 75 may also be used for withdrawing preservative from the oil-storage 90 tank and forcing the same into the measuring and oil working tanks, if desired. This is accomplished by closing valves 90 and 86 and opening valves 87, 84, 83 and 88, in which case the preservative will be drawn 95 through pipes 78, 82 and 74 into the pump 75 and discharged through the pipes 76 and 77.

By employing air storage tanks, the desired pressure necessary for treating the 100 charges of timber may be maintained by operating the small capacity pumps 12 and 13 over extended periods of time and under conditions most suitable to the plant as a whole, and the necessary vacuum may 105 be similarly maintained by means of small economical vacuum pumps 63 and 64. These smaller pumps may be operated more economically, due to the fact that they do not necessitate actuation at their maximum capacities, obviating the necessity of subjecting the said units or the plant to peak loads. Also, due to the fact that high pressure air and vacuum are available at all 110 times, the time of treatment is reduced to a minimum. Besides relieving the units and plant from operation at peak loads and reducing the time of treatment, hence increasing the output of the plant, due to the feeding of the preservative into the treating cylinder quickly, all portions of the timber-charges are subjected to substantially 115 the same action from the preservative regardless of its location within the treating cylinder, the treated material, therefore, being of substantially uniform character.

It is thus seen that the invention provides a plant which is comparatively free from complicated mechanisms, is economical to 120 install, is efficient in operation, possesses a 125

large capacity, produces a product which is of uniform character, and which obviates the necessity of operating the same under objectionable and uneconomical peak loads.

5 I claim:

1. A wood treating apparatus comprising a treating cylinder, a superposed measuring tank, a conduit leading from the measuring tank to the treating cylinder, an air storage tank, a conduit establishing communication between the storage tank and measuring tank, the relative sizes of the air storage tank and measuring tank being such that the desired maximum pressure in the treating cylinder may be quickly obtained by causing equalization of the pressures in the said tanks.
- 10 2. A wood treating apparatus comprising a treating cylinder, a superposed oil working tank, a superposed measuring tank, conduits connecting the oil-working and measuring tanks to the treating cylinder, an air storage tank, a conduit establishing communication between the storage tank and measuring tank, the relative sizes of the air storage tank and measuring tank being such that the desired maximum pressure within the treating cylinder may be quickly obtained by causing equalization of the pressures in the last named tanks.
- 15 3. A wood treating apparatus comprising a treating cylinder, a superposed oil-working tank, a measuring tank, disposed in one end of the oil-working tank, a conduit connecting the bottoms of the oil working tank and treating cylinder, a conduit leading from the bottom of the measuring tank to the top of the treating cylinder, an air storage tank, a conduit establishing communication between the storage tank and measuring tank, the relative sizes of the air storage tank and measuring tank being such that the desired maximum pressure within the treating cylinder may be quickly obtained by causing equalization of the pressures within the last named tanks.
- 20 4. A wood treating apparatus comprising a treating cylinder, a superposed oil measuring tank, a conduit establishing communication between the measuring tank and treating cylinder, an air storage tank, a conduit leading from the air storage tank to the measuring tank, the relative sizes of the air storage and measuring tanks being such that an equalization of pressures therein will

result in the desired maximum pressure to be established in the treating cylinder, a vacuum tank, a pipe connecting the vacuum tank and treating cylinder, the vacuum tank being of such proportions relative to the treating cylinder that an equalization of the pressures within the vacuum tank and treating cylinder will quickly produce the predetermined low pressure desired therein.

5. A wood treating apparatus comprising a treating cylinder, a superposed oil-working tank, a superposed measuring tank, a conduit connecting the bottoms of the oil-working tank and treating cylinder, a conduit leading from the bottom of the measuring tank to the top of the treating cylinder, an air storage tank connected to the measuring tank, a vacuum tank connected to the treating cylinder, and means to maintain the desired pressures in the said air storage and vacuum tanks.

6. A wood treating apparatus comprising a treating cylinder, a superposed oil-working tank, a superposed measuring tank, a conduit connecting the bottoms of the oil-working tank and treating cylinder, a conduit leading from the bottom of the measuring tank to the top of the treating cylinder, an air storage tank connected to the measuring tank, a vacuum tank connected to the treating cylinder, a condenser interposed between the treating cylinder and vacuum tank, and means to maintain the desired pressures in the said air storage and vacuum tanks.

7. A wood treating apparatus comprising a treating cylinder, a superposed oil-working tank, a superposed measuring tank, conduits connecting the tops and bottoms respectively of said oil-working tank and treating cylinder, a pipe leading from the bottom of the measuring tank to the top of the treating cylinder, an air storage tank, connections between the air storage tank and the treating cylinder, oil-working tank and measuring tank, a vacuum tank, a conduit leading from the treating cylinder to the vacuum tank, and means for maintaining the desired pressures within the air storage and vacuum tanks.

In testimony whereof I sign my name.
GRANT B. SHIPLEY.
